ISOLATED RADIANT ENERGY CONTROL
SYSTEMJames Y. Dunbar, Robert D. Gilpin, and Norman
R. Hussey, United States Navy

Application March 19, 1945, Serial No. 583,484

5 Claims. (Cl. 250—2)

(Granted under the act of March 3, 1883, as
amended April 30, 1928; 370 O. G. 757)

1

This invention relates generally to a remote control system, and more particularly to the radiant energy controlled type, isolated from enemy jamming and local interference for use in controlling robot planes and bombs.

The principal object of this invention is to provide a radiant energy remote control system, wherein the reception of radiant energy is insensitive to signals from any point ahead of the line of flight.

Another object of this invention is to provide a radiant energy remote control system in which the vibratile control elements are isolated from airborne sound, vibration, and shock.

A further object of this invention is to provide a radiant energy remote control system in which changes in carrier wave frequency do not affect operation.

A still further object of this invention is to provide a radiant energy remote control system responsive to selected control frequencies.

Another object of this invention is to provide a mechanical device that builds up a large amplitude response to weak energy impressions.

Another object of this invention is to provide a method for directing a robot to a target.

Another object of this invention is to provide a resonant electro-mechanical switch.

The invention will now be described with reference to the accompanying drawings, in which:

Fig. 1 is a wiring diagram of the invention;

Fig. 2 is a front elevational view of the reed tube;

Fig. 3 is a side elevational view of the reed tube;

Fig. 4 is a bottom view of Fig. 3; and

Fig. 5 is a bottom view of an octal socket for tube of Fig. 2.

A dipole directional antenna 1 is grounded through coil 2. Said coil 2 is inductively coupled with tank circuit coil 3 of the regenerative detector 4. The tank coil 3 is center tapped at 5 so as to include a portion of said coil 6 in the plate circuit 7, leaving the remainder 8 in the grid circuit 9. The magnetic coupling between the two portions of the coil 3, namely the plate circuit portion 6 and the grid circuit portion 8, provides the regenerative feedback. Said feedback can be adjusted by moving the position of the tap on said coil 3. The resistance 10 and the condenser 11, in parallel in the grid circuit, enable the triode 12 to be used as a detector without the use of a C battery. Said grid leak resistance and condenser maintain the grid bias at a proper negative potential for detection by well

known principles of grid leak biasing. The plate circuit leading from said regenerative detector 4 is connected to a T type radio frequency filter 13 composed of radio frequency choke coils 14 and 15 and a grounded radio frequency bypass condenser 16. The cathode 17 of said triode 12 is grounded. The output terminal of said choke input filter 13 is connected to the primary 18 of transformer 19, and the potentiometer 20, in series. Potentiometer moving contact 21 controls the potential in the plate circuit by selectively varying the resistance 22. One end of the potentiometer resistance 22 is grounded at 23, and the other end is connected to the positive terminal of grounded battery 24, with a resistance 25 and a switch 26, in series, therebetween.

The secondary 27 of transformer 19 has one of its output terminals connected to the grid and the other terminal to the cathode of triode 28.

Resistor 29 is connected across secondary 27. Cathode resistor 30 with shunt capacitor 31 are connected to cathode of triode 28 and grounded at 32.

The plate of triode 28 is connected to one of the primary coil 33 terminals of transformer 34. The other of said primary coil terminals is connected to contact 35 of switch 26.

Current for the tube heater elements 36 and 37 is supplied by a battery 38 which is electrically connected thereto, and also grounded at 38. Switch 39, inserted in the heater circuit, controls the current therein.

Secondary 40 of transformer 34 has one of its ends connected to terminal 41 and the other end to terminal 42 of box 43. Said terminals 41 and 42 pass through the wall of acoustic isolation box 43, so that they serve as terminals on the inside of the box as well as on the outside of said box.

The acoustic isolation box 43 is designed in the conventional manner to isolate the following vacuum tube and relay switches, to be mounted therein, from airborne sound, vibration and shock.

Tube 44 consists of an envelope 45 mounted on an octal base 46 to fit a standard octal socket. Said arrangement is hermetically sealed and evacuated. The envelope encloses a plurality of ferrous reeds 54, 55, 56 and 57, vertically mounted, as by welding, on a heavy conducting base 47 that is securely carried by the octal base 46 and insulated therefrom. Said heavy conducting base 47 is electrically connected to base pin 48 in the usual vacuum tube manner. Yoke contacts 49, 50, 51 and 52 are secured to support 53 in a co-operating relation with the free ends of reeds

54, 55, 56 and 57, respectively. Said support 53 is of non-conducting material and mounted to base 47 by any usual means. The yoke contacts 49, 50, 51 and 52 are electrically connected to base pins 58, 59, 60 and 61, respectively, in the usual vacuum tube manner. Electromagnet 62, securely mounted on heavy base 47, and separated therefrom by insulator 63, is positioned in close proximity to said ferrous reeds so that the reeds can be magnetically actuated thereby. Said electromagnet is electrically connected to base pins 64 and 65 in the usual vacuum tube manner, thence to terminals 41 and 42 for outside connections.

The reeds 54, 55, 56 and 57 have a natural mounted frequency of 8, 10, 12 and 15 cycles per second, respectively. However, reeds of any other natural frequency can also be used. All of said elements are mounted in a vacuum. The damping caused by air is thus removed and the resonance curve of the reed becomes very sharp, so that several reeds may have natural frequencies very close to each other and operated by a single magnet. In such a group only the reed having a frequency the same as that given to the pulsatingly energized magnet will operate, the others not so tuned remaining relatively stationary. It is a physical fact that if the forcing frequency is the same as the natural frequency of a system having low damping, very large amplitudes of vibration may be expected.

When the weak magnetic impulses resulting from weak radiant energy waves are applied to a reed, the amplitude of the reed progressively increases until contact is made with its associated yoke contact which closes a circuit that energizes and actuates a relay, with or without a time delay mechanism. A motor is thereby operated which controls the control surfaces of a robot flying apparatus.

The assembled tube 44 is inserted in a standard octal socket that is suspended in acoustic isolation box 43 so that the natural frequency of the suspension is well below that of any of the reeds, thereby insuring that no false impression of the reeds from undesirable sources can take place.

Within this same acoustic box 43 are mounted four relay switches 66, 67, 68 and 69 of conventional construction, which control motors 70 and 71 located outside said acoustic box 43. Relay 66 controls motor 70 in clockwise direction; relay 67, in counter-clockwise direction. Relay 68 controls motor 71 in clockwise direction; relay 69, in counter-clockwise direction.

Electromagnet base pins 64 and 65 are connected across secondary coil terminals 41 and 42.

Conductor 72 electrically connects contact 73 of switch 39 with reed base 47, through pin terminal 48. Grounded moving coils 74, 75, 76 and 77 are electrically connected to pin terminals 61, 60, 59 and 58, respectively. In other words, the reeds 54, 55, 56 and 57, their associated yoke contacts 44, 50, 51 and 52, and their related relay moving coils 74, 75, 76 and 77, respectively, are connected in parallel across battery 94.

Relay armatures 78, 79, 80 and 81 with their associated fixed contacts 82, 83, 84 and 85, and their related motor reversing field coils 86, 87, 88 and 89, respectively, are connected in parallel across battery 94.

Motors 70 and 71, with their paired reversing coils 86, 87, 88 and 89, respectively, are located outside of box 43 and are connected to their associated relays 66, 67, 68 and 69 through means of contacts 90, 91, 92 and 93, respectively, which pass through the walls of said box 43 and serve

as terminals inside as well as outside of said box. The reversible motors 70 and 71 are mechanically connected to those elements of a robot plane or bomb that control the vertical and horizontal control surfaces such as elevators or rudders.

Operation

A transmitter generates and modulates or interrupts the radio-frequency power that its associated antenna converts into electromagnetic radiation. The carrier wave is amplitude modulated to a constant frequency of 8, 10, 12, or 15 cycles per second. Other frequencies may be used depending on the natural frequencies of the responding reeds used in the receiver. In this construction, the reeds 54, 55, 56 and 57 have a responding natural frequency of 8, 10, 12 and 15, respectively.

As the transmitted radiant energy wave cuts across the dipole directional antenna 1, a similar voltage is generated in the antenna ground system, consisting of antenna 1, coil 2, and ground. This system is connected to the regenerative detector 4 by means of transformer coupling between antenna coil 2 and tank circuit coil 3. Dipole directional antenna 1 is insensitive to signals from any point ahead of the line of flight, thereby insuring freedom from jamming or enemy interference.

The output of regenerative detector 4 is fed into filter 13 wherein the audio frequency is separated from the radio frequency.

The audio frequency output from filter 13 is fed into coupling transformer 19 which feeds into amplifier 28.

Said amplified signal is transformer coupled to and fed into reed switch tube 44, through means of coupling transformer 34.

As the audio frequency voltage energizes electromagnet 62, magnetic impulses are applied to the reeds 54, 55, 56 and 57, having natural frequencies of 8, 10, 12 and 15 cycles per second, respectively. The sending station transmits a wave modulated at any of these frequencies. If the transmitted impulse is 10 cycles per second, only reed 54 having a natural frequency of 10 cycles per second will respond in resonance, contact will be made with its associated yoke contact 49, relay switch 64 energized and actuated to a closed position, motor 71 started thereby, and the control surfaces of a plane or robot actuated in a way that will result in the plane or robot ascending "up." Similarly, a plane or robot can be controlled to move "down," "left" or "right," through means of corresponding circuits disclosed.

The reed switch tube 44 is mounted in an acoustic isolation box 43, to isolate the reeds from airborne sound stimulation.

The switch tube 44 is additionally isolated from interference by suspending it on shock absorbing and vibration damping means, such as light springs, to prevent the reeds being influenced by extraneous forces. The natural frequency of the suspension is well below that of any of the reeds, so that no false operation of the reeds from undesirable sources takes place.

The invention described herein may be manufactured and used by or for the Government of the United States of America for governmental purposes without the payment of any royalties thereon or therefor.

What I claim is:

1. In a radiant energy remote control system having a transmitter for transmitting radiant energy signals of predetermined frequencies; an

airborne object having control surfaces; a directional receiving antenna mounted on said airplane, insensitive to signals from any point ahead of the line of flight; and a detector coupled to said antenna; the combination, comprising: an evacuated envelope; a plurality of reeds mounted therein, having natural frequencies corresponding to the signal frequencies; isolating means surrounding said envelope to isolate against airborne sound, vibration, and shock; an electromagnet energizable by the output of said detector for vibrating said reeds; contact means engaged by the reeds when the vibration reaches a predetermined amplitude; a plurality of relays controlled by said contact means; and a plurality of motors controlled by said relays for actuating said control surfaces.

2. In a radiant energy remote control system, having means for transmitting radiant energy signals of predetermined frequencies; a flying object having control surfaces; and means for receiving and detecting said radiant energy signals mounted on said flying object, insensitive to signals from any point ahead of the line of flight; the combination, comprising: an evacuated envelope; vibratile means having natural frequencies corresponding to said signal frequencies mounted therein; isolating means for isolating said vibratile means against airborne sound, vibration and shock; contact means engageable by said vibratile means, respectively; electromagnetic means energizable by said received signal, for actuating said vibratile means into engagement with said contact means; and external circuits actuated by the engagement of said vibratile means and said contact means for controlling said control surfaces.

3. In a radiant energy remote control system having means for transmitting a radiant energy signal; a movable object having control means; and means for receiving said radiant energy signal mounted on said movable object, insensitive to signals from any point ahead of the line of movement; the combination, comprising: vibratile means having natural frequencies corresponding to the frequencies of said signal; contact means engageable by said vibratile means; electromagnetic means energizable by said signal for actuating said vibratile means into engagement with said contact means; and operating circuit means, adapted to be connected to said control means, operable by the said engagement for controlling said movable object.

4. In a remote control radiant energy receiver having a receiving antenna responsive to signals of a predetermined frequency from a predetermined direction and a detector coupled to said antenna, the combination comprising: an evacuated envelope; a plurality of reeds mounted therein, having natural frequencies corresponding to said signal frequencies; a plurality of contacts positioned within said envelope and engageable by said reeds, respectively; isolating means surrounding said envelope to isolate against airborne sound, vibration and shock; an electromagnet energizable by the output of said detector for vibrating said reeds electromagnetically; and external circuits actuated by the engagement of any one of said reeds with its associated contact when the vibration reaches a predetermined amplitude.

5. In a remote control radiant energy receiver having means for receiving modulated radiant energy responsive to signals from a predetermined direction, the combination comprising: vibratile means having natural frequencies corresponding to the frequencies of the modulation components of said radiant energy; contact means engageable by said vibratile means, respectively; electromagnetic means energizable by said received radiant energy for actuating said vibratile means; and external circuits operable by the engagement of said contact means and said vibratile means.
